(57) **CLAIM**

The ornamental design for a privacy panel, as shown and described.

DESCRIPTION

FIG. 1 is a front view of a privacy panel showing our new design;

FIG. 2 is a left side view thereof;

FIG. 3 is a front view of a second embodiment thereof; and,

FIG. 4 is a left side view thereof.
The broken lines illustrate unclaimed environmental structure and form no part of the claimed design.
